M. H. MANN

TELEPHONE DIRECTORY STAND

Filed Sept. 24, 1924

UNITED STATES PATENT OFFICE.

MILTON HENRY MANN, OF SAN FRANCISCO, CALIFORNIA.

TELEPHONE-DIRECTORY STAND.

Application filed September 24, 1924. Serial No. 739,634.

To all whom it may concern:

Be it known that I, MILTON HENRY MANN, a citizen of the United States, and a resident of San Francisco, county of San Francisco, 5 State of California, have invented a new and useful Telephone-Directory Stand, of which the following is a specification.

This invention relates to telephone stands and directories and has for its primary object the provision of novel means for displaying the names and telephone numbers of telephone subscribers so that convenient reference can be had thereto when their use is desired.

Another object of the invention is to provide a device of this character having a transparent table top and means for holding an indicia bearing sheet with respect thereto so that written information contained thereon will be preserved against accidental obliteration incident to constant usage of the telephone, and wherein means are employed to support the telephone instrument to a point at one side of said indicia bearing sheet.

Another object of the invention is to provide a novel device of this character which will function as aforesaid and consist of an arrangement of parts which combine to provide an attractive article of furniture.

Other features of novelty and utility will obviously appear upon reference to the accompanying drawings and description, wherein—

Figure 1 is a perspective view of a preferred embodiment of the invention,

Figure 2 is a section on line II—II of Figure 1,

Figure 3 is a transverse section through 40 the device showing a slightly modified form thereof,

Figure 4 is a perspective view of the form of board or slide employed in Figure 2, and

Figure 5 is a section through a further modified form of slide or board.

In carrying the invention into practice, use is made of the legs 5 to support a frame 7 in which a transparent top or glass panel 6 is mounted. This panel is set in the frame 7 so that it lies flush with the upper surface thereof as shown in Figures 1 and 2.

Beneath the panel and secured in any suitable well known manner to the frame 7 are channeled strips 8—8, the same being spaced from the panel as shown in Figure 2 so that a plurality of guideways are formed

under the panel. Two of these guideways, indicated by 9, are disposed one alongside the other and below a third, indicated by 9'. A board 10 is slidable in guideway 9' and through a recess 1 in one end of frame 7. The board provides a support for a card or sheet 11 bearing the desired directory information, such as the names of certain telephone subscribers together with their telephone numbers. This information can be arranged on both sides of the sheet 11 in order that the sheet can be reversed and both sides employed as indicia bearing surfaces.

The sheet may be secured to the board by means of thumb tacks or the like. When the board 10 is in the position shown in Figures 1 and 2, the sheet 11 is disposed directly beneath the transparent panel 6 where the subscribers' names and telephone numbers will be clearly discernible through said panel. The board is provided with a finger engaging flange 12 which may be conveniently manipulated when adjusting the board beneath said panel. This flange lies flush with the outer surface of the frame when the board is positioned as shown in Figures 1 and 2.

In opposite sides of frame 7 are recesses 3 which communicate with the guideways 9—9' which receive the slides 13—13. A telephone instrument A can be mounted on either one of these slides where it will be disposed at one side of said panel in order that the directory surface of the sheet 11 will not be obliterated or concealed in any way when the phone is used.

Under the frame 7 and secured to the legs of the table is a shelf 14 on which the telephone book may be mounted.

In Figures 3 and 4 I employ a board 15 having parallel slots 16—16 in which rollers 17—17 are journaled. Associated with this board and passing over the respective rollers is an endless indicia bearing sheet 18. In this form, names of telephone subscribers can be arranged throughout the sheet and the latter turned or adjusted with respect to the panel 6 so that a selected portion of the sheet can be brought to view when its use is desired. One half of this sheet may be decorated or ornamented in any suitable well known manner and normally arranged under the panel 6 in order to appeal to the aesthetic and contribute to the attractiveness of the device as an article of furniture. This is particularly appropriate when the device

is used in residences, apartments or the like. When the device is used in offices or for commercial purposes, it is desired that this feature be omitted in order that a large number 5 of telephone subscribers' names and numbers can be arranged in a minimum field.

In Figure 5, I show a board 19 having sheets 20—20 secured to its respective sides. The front end of the board is provided with 10 a manipulating flange 21. In this form, the board is freely reversible so that either one of its sides can be arranged under the glass panel to be visualized therethrough.

I claim:

15 A top for tables, stands and the like comprising a frame adapted to embrace the upper end portions of the legs of a table and to be connected thereto and to be supported horizontally thereby, said frame having its 20 lateral portions constructed relatively thick and deep and depending from the edge por-

tions of the upper face of the frame, certain of said lateral portions having transverse recesses, and guideways extending transversely of the frame and forming extensions of said recesses, certain of said guideways being arranged one above the other in parallel horizontal planes, slidable boards closely fitted in said guideways and extending at one end through the recesses and constructed so that their outer end surfaces extend flush with the outer surfaces of the recessed lateral portions when the boards are wholly disposed in the guideways and recesses whereby the outer faces of said lateral portions 35 may appear continuous, the inner edge of said frame having a rabbet and a horizontally extending transparent plate wholly disposed in the said rabbet and forming a continuation of the upper surface of the frame 40 and constituting a panel.

MILTON HENRY MANN.
